UNITED STATES PATENT OFFICE.

IDA C. HINE, OF NEW YORK, N. Y.

DESIGN FOR A BUTTON.

SPECIFICATION forming part of Design No. 18,743, dated November 20, 1888.

Application filed August 8, 1888. Serial No. 282,251. Term of patent 3½ years.

To all whom it may concern:

Be it known that I, IDA C. HINE, a citizen of the United States, and a resident of New York city, in the county of New York and 5 State of New York, have invented and produced a certain new and useful and original Design for Buttons, of which the following is a specification, reference being had to the accompanying drawing, forming part thereof.

- 10 My invention consists in a new design for buttons, as fully set forth in the following specification and illustrated in the accompanying drawing, which represents a face view of a button containing my design.
- 15 The leading feature of my design is a button having an annular shape and surface ornamentation consisting of lines of light squares on a dark surface, having a rectangular space in the center of the button for any suitable word 20 or words, as is shown in the accompanying drawing, which is, however, magnified.

In the drawing I show the face of a button, on one portion of which face a rectangular space across the center of the button is reserved for any suitable word or words.

25 *a a* are lines of light squares upon the gen-

eral face *b* of the button, the general face of the button being darker than these squares. There are also between these lines of squares single squares *c c*. There is always a hiatus 30 in the lines of squares just above and below such single squares. In the center of all the squares is a dot, as shown in the drawing, of about the same darkness as the general face of the button.

35 What I claim as new, and desire to secure by Letters Patent, is—

The design for a button having the annular shape and surface ornamentation consisting of a dark general surface, *b*, of the button, in the center of which is reserved a rectangular space for any suitable word or words, and light squares *a a*, arranged upon this dark general surface *b*, substantially in the manner described and shown.

40 Signed at New York city, in the county of New York and State of New York, this 4th day of August, A. D. 1888.

45 IDA C. HINE.
